UNITED STATES PATENT OFFICE.

LEWIS P. HALLADAY, OF MARION, INDIANA.

DESIGN FOR A CLAMP FOR BICYCLE-HANDLES.

SPECIFICATION forming part of Design No. 26,361, dated December 1, 1896.

Application filed May 9, 1896. Serial No. 590,950. Term of patent 8½ years.

To all whom it may concern:

Be it known that I, LEWIS P. HALLADAY, a citizen of the United States, residing at Marion, in the county of Grant, in the State 5 of Indiana, have invented a certain new and useful Design for a Clamp for Bicycle-Handles, of which the following is a description.

My invention relates to a design for handle-bar devices for bicycles. It is illustrated in 10 the accompanying drawings, wherein—

Figure 1 is a plan view of a bicycle-handle clamp, showing my design. Fig. 2 is a side elevation of the same. Fig. 3 is a front view.

Like parts are indicated by the same letter in all the figures.

The leading feature of my design consists in a ring-like portion having a raised rounded

rib across one exterior surface and at the opposite end of the same radius a flange-like portion. The clamp has also the inside projections, as shown. 20

Referring to the parts by letter, A is one half of the frame; B, the other half; C D, the two parts which together make the rounded ring; E F, the two parts which together make 25 the projecting flange, and G G the internal projections.

What I claim is—

The design for a clamp for bicycle-handles, substantially as shown and described.

LEWIS P. HALLADAY.
